UNITED STATES PATENT OFFICE.

WILLIAM H. SHETTERLY, OF KALAMAZOO, MICHIGAN.

HAMMOCK-SPREADER.

SPECIFICATION forming part of Letters Patent No. 560,285, dated May 19, 1896.

Application filed June 6, 1895. Serial No. 551,863. (No model.)

To all whom it may concern:

Be it known that I, WILLIAM H. SHETTERLY, a citizen of the United States, residing at Kalamazoo, in the county of Kalamazoo, State 5 of Michigan, have invented a new and useful Hammock-Spreader, of which the following is a specification.

This invention relates to hammock-spreaders which are made in detachable sections; 10 and it has for its object an improved coupling for the purpose substantially as below described and claimed.

In the drawing forming a part of this specification is shown an elevation of the coupling, a portion being in section and the outer 15 end of the spreader-sticks being broken off.

The coupling for detachably attaching the sticks A (shown at D) is made of metal and in two parts. It is tubular in form and prefer- 20 ably made on a longitudinal curve corresponding to the curve of the hammock-sticks

A. The part L has a core in one end to receive the end of one of the sticks A, in which it is rigidly attached at I, and the other end 25 P is tapered. The other part E of the coupling is provided with a core in each end, one of which is funnel form or internally tapered to detachably receive the tapered end P of

the other part L, and the other core of part E receives the end of the other stick A, in 30 which it is rigidly attached at I. These two parts of the coupling D form ferrules to the end of the sticks A A, and in coupling metal is attached to metal instead of coupling wood with metal, in which case the wood is liable 35 to shrink or swell or become unduly worn so as not to make a desirable fit.

Having thus described my invention, what I claim as new, and desire to secure by Letters Patent of the United States, is—

In a hammock-spreader, the metal coupling composed of two metal parts, each part cored out in its outer end to receive the hammock-sticks, one of said metal parts having its inner end tapered, and the other part having a 45 funnel-shaped core in its inner end to receive the inner end of the other part, and both parts being rigidly attached to their respective hammock-sticks, substantially as set forth.

In testimony of the foregoing I have here- 50 unto subscribed my name in the presence of two witnesses.

WILLIAM H. SHETTERLY.
